LOOSE-LEAF POST BINDER

Samuel Segal, New York, N. Y., assignor to Wilson-Jones Co., Chicago, Ill., a corporation of Massachusetts

Application August 7, 1944, Serial No. 548,431

23 Claims. (Cl. 129—21)

1

The subject matter of this invention is a loose leaf binder of the type wherein a stack of papers are guided on sectional posts and removably interposed between a post support and a clamping follower. Specifically the invention deals with improved detachable sectional posts for loose leaf binders for extending or reducing the stack capacity between the post support and clamping follower. Where sectional posts are utilized in loose leaf binders, the base section thereof is generally spun on and fixedly secured to the lower wall of the post supporting flattened tube. In many instances during use the base section of a sectional post becomes loose and undesirably rotates, consequently causing the whole sectional post assembly to bodily turn with it. Also in practice it is difficult to repair the base section in that it is not removably connected to its supporting tube. One of the objects of the present invention is to eliminate these disadvantages in the provision of spaced paper guiding sectional posts having base sections removably but non-rotatably interlocked with the lower wall of the post supporting flattened tube and sustained against involuntary tilting by the upper wall of the supporting flattened tube, and associated with movable means displaceable relative to the base section and cooperating with the upper wall of the supporting flattened tube to preclude longitudinal displacement of the base section. A further object of the invention is realized in permitting the sectional posts to be quickly and readily assembled and desirably secured to the supporting flattened tube. A further and important object is concerned with the provision of means to prevent the base section of the sectional posts from turning or becoming loose. Another object is realized in the provision of a slotted post base section and superimposed detachably associated slotted intervening and top-most post sections for cooperating with novel wrench means adapted to bodily receive these sections and removably interlock selectively with the longitudinally arranged slots of these sections for coupling or unfastening the latter selectively.

In the drawings:

Fig. 1 is a fragmentary view of the loose leaf binder showing one embodiment of the sectional posts according to my invention.

Fig. 2 is a vertical sectional view on the line 2—2 of Fig. 1, however, illustrating the clamping follower in dash and dot lines.

Fig. 2^a is a fragmentary view of Fig. 2 particularly illustrating the rotatable sleeve associated

2

with the base section of a post removably locked to the post supporting tube.

Fig. 2^b is a detailed view of Fig. 2^a.

Fig. 3 is a fragmentary perspective and exploded view of Fig. 1.

Fig. 4 is a sectional view on the line 4—4 of Fig. 2.

Fig. 5 is a plan view of a wrench according to the invention.

Fig. 5^a is a perspective view of a lower sectional post.

Fig. 6 is a view similar to Fig. 2, depicting a slightly modified sectional post.

Fig. 7 is an exploded perspective view of Fig. 6.

Fig. 8 is a view similar to Fig. 7 illustrating a sectional post according to Fig. 2.

Fig. 9 is a sectional view on the line 9—9 of Fig. 10.

Fig. 10 is a sectional view on the line 10—10 of Fig. 9.

Fig. 11 is an exploded perspective view of a sectional post utilizing the pin anchoring means illustrated in Figs. 9 and 10.

Fig. 12 is a view similar to Fig. 11 showing a sectional post of the type illustrated in Fig. 2.

Fig. 13 is a broken elevational view of a sectional post, partly in section of the type illustrated in Fig. 11 however removably anchored to the lower hollow supporting bar by a slidable insert.

Fig. 14 is a longitudinal sectional view on the line 14—14 of Fig. 13.

Fig. 15 is a vertical sectional view on the line 15—15 of Fig. 14.

Fig. 16 is a perspective and exploded view of Fig. 13, and

Fig. 17 is a view similar to Fig. 16 however illustrating another form of a slidable locking insert.

Illustrative of the embodiments disclosed, the loose leaf binder is generally denoted B and comprises a pair of spaced covers C swingably attached to upper and lower spaced tubular bars or headers F and S respectively. For purposes of specification, tubular bar S may be considered as a support for the pair of spaced sectional posts P on which the stack of papers PP are removably mounted. The bar F is a compressor or follower for desirably and closely holding the stack of papers against the lower supporting bar S as is well understood in the art.

According to the embodiment illustrated in Figs. 1—4 the lower supporting bar S has its bottom flat wall provided with a pair of spaced cir-

cular openings as 11, each interrupted by a bridge or key 12 to define spaced openings or key receiving means and has its upper flat wall 14 provided with a pair of spaced circular openings 15 registering with the lower circular openings 11, and each opening 15 merges with a notch or keyway 16 for purposes hereinafter set forth.

Alined or registering openings 11 and 15, position or locate the lower or base sections 17 of the sectional posts P relative to lower bar S. To this end, each of the lower sections 17 is provided with a cylindrical head 18 characterizing spaced keys removably and closely fitting into and positioned by the wall of opening 15 and having the diametrically disposed slot 19 or keyway for closely and removably receiving the bridge or key 12, the latter serving as stop means to limit the insertion of the lower base sections 17 into the supporting flattened tube S.

For anchoring the lower sections 17 to the supporting tube or bar S, clamping means in the form of split sleeves 20 are utilized. Each of these sleeves is split lengthwise to provide a keyway or slot 21. These sleeves closely and rotatably but frictionally and resiliently surround the cylindrical body of the lower sections 17 and each sleeve 20 is characterized by an outwardly extending wing portion or key 22.

Each of the lower post sections 17 may be considered as bearing means for the concentrically arranged rotatable sleeves 20 and when these parts are assembled, wing portions 22 may be conveniently received in notches as 16 for facilitating reception of the slotted head 18 on the cooperating bridges 12. However the walls of openings 15 characterize means closely and removably encompassing the sleeves 20 while heads 18 serve to limit displacement of sleeves on the lower sectional posts 17.

By utilizing either end of the wrench W shown in Fig. 5, the anchoring sleeves 20 may be selectively rotated relative to the supporting bar S and its bearings or lower base sectional posts 17 and the key or wing 22 which is under the top wall 14 of the lower supporting bar is rotated to clear or be out of alinement with notch 16 and inasmuch as its length closely approximates the distance between the lower and upper flat walls 10 and 14, the lower or post base sections 17 are removably locked and retained against longitudinal displacement by reason of the cam faces 22' frictionally engaging the inner surface of the upper wall 14.

Specifically the wrench W embodies a hooked end 23 and a perforated end 24 having its circular opening 25 interrupted by a lug or key 26. As previously stated, either end of wrench W may be employed to rotate a locking sleeve 20 of a base section 17. If this hooked end 23 be positioned in keyway 21 or if the perforated end 24 be shifted over the resilient sleeve to position key 26 into the walls of its slot or gap as 21 the sleeve upon actuation of the wrench may be rotated to a locking relation if unlocked or to an unlocked relation if locked as is well understood.

In Fig. 1 each sectional post is shown as having three sections, to wit, 17, 21 and 28. Of course as the stack of papers becomes larger intervening sections as 21 may be provided. And where the stack is reduced these intervening sections may be eliminated. It should be understood, however, that each of the intervening post sections as 21 and its topmost sections 28 each include an elongated slot or keyway 29 running lengthwise thereof to coat with either end of wrench W for 75

detaching from or attaching the post sections to each other. For this purpose in the form according to Figs. 1 and 2 the upper portions of the lower and intervening post sections 17 and 21 each embody threaded stems 30 (also illustrated in Fig. 8) removably connected to the threaded recess 31 in the lower portions of the intervening and topmost post sections 21 and 28.

In all of the embodiments disclosed, the lower base sections of the several sectional posts are removably locked relative to the lower supporting bar S, and thus may be if desired readily and quickly replaced by other similar base sections. Moreover each of the base sections 17 is provided with non-circular means removably interlocked with the lower wall of the bar S and consequently is prevented against turning. Furthermore the topmost and intervening sections are not only removably mounted but the keyways as 29 provide means for facilitating assembly of these parts in that the wrench may be quickly fitted over one of the post sections to removably interlock key 26 in keyway 29 instead of fumbling needlessly in the attempt to thread the hooked end or crank 23 of the wrench into a conventional perforation (not shown) on the post sections although by the present invention the hooked end 23 may be still employed in connection with actuating or rotating the slotted sections of the sectional posts herein described.

Where the sleeve 20 has been rotated to permit the cam portion 22' to frictionally lock with the lower bar S (Fig. 4), base section 17 is held against longitudinal displacement by wing 22 abutting the inside faces of the lower and upper walls 10 and 14, is held against rotational displacement by the spaced keys defined by the slotted head 18 cooperating with bridge 12, and is held against lateral displacement due to the close but removable fit of the sleeve 20 in the opening 15 in the upper wall 14 which serves in effect as reinforcing means to preclude accidental tilting of a base section 17.

By unthreading the sections 28, access may be had to the intervening sections 21 for unthreading the latter although access to the entire sectional post P may be had by simply removing the upper cover C and thereafter each sectional post P may be removed as a unit if desired by utilizing the wrench W and rotating its respective sleeve 20 until its cammed wing 22 registers with its cooperating slot 16 and subsequently the sectional post may be removed as a unit from bar S. It is apparent therefore, that not only may each of the sections of the sectional post be readily dismantled but each sectional post may be removed bodily from the supporting bar S.

In the form according to Figs. 6 and 7, the lower or base sections 17 are each provided with a non-circular key or lug 35 removably and closely positioned in a correspondingly shaped opening or key receiving means 36 in the bottom flat wall 10 of the hollow supporting bar S for removably locking base section 17 against rotation. Lug or key 35 depends from head or flange 37 removably seated against the flat wall 10 while sleeve 20 is seated on the annular stop flange 37. In other aspects the embodiment illustrated in Figs. 6 and 7 is along the lines of form shown in Figs. 1-3 except that the base section 17 and intermediate section 21 each include a threaded recess 38 for removably receiving the depending threaded stems 39 of the intervening and topmost sections 21 and 28.

In connection with the form illustrated in

Fig. 8, the construction is along the lines of the embodiment disclosed in Figs. 6 and 7 except the stems 30 of the base and intervening sections 17 and 21 cooperate with the threaded sockets or recesses 31 in the intervening and topmost sections 21 and 23 as in the case of the form shown in Figs. 1-3 inclusive.

Coming now to the form illustrated in Figs. 9-11 wherein the base section 17 is removably sustained by the expanded intermediate portions 40 of the slidably guided looped spring or pin 41 disengageably interlocking with the walls of groove 43. It will be noted that the reduced portion 44 is resiliently and removably straddled by the arms of the pin or loop 41 and the arms of the loop cooperate with wall 14 to hold base section 17 against longitudinal displacement, that is, against withdrawal from the bar S. After section 17 is positioned in the tube S, it is also locked by the hair pin shaped loop as previously stated and to remove the pin the crank portion 23 of the wrench may be utilized to act against the closed end 45 of the looped pin as indicated in Fig. 10. In other aspects, the form shown in Figs. 9-11 is along the lines of the form illustrated in Figs. 6 and 7.

The embodiment illustrated in Fig. 12 conforms to the species shown in Fig. 11 except that the base and intervening sections are provided with threaded stems for removably threading into threaded sockets in the lower portions of the intervening and topmost sections.

In Figs. 13-16, the form illustrated is along the lines of the embodiment according to Fig. 11 except that the locking pin has been replaced by a slideable spring plunger or insert 50 having a tail portion 50' provided with the key shaped slot 51 and embodying the dependent curved wings 52 merging with the closure head 53' terminating in a lower wall 54' receivable in the bore of the flattened tube S.

In the matter of assembly, spring insert 50 is first telescoped partly within the tube S so that the expanded portion 53 of opening 51 registers with the aligned openings 36 and 15 of tube S. Hence base section 17 may be inserted into and through openings 15 and 53 to position key or lug 35 into the key receiving means or opening 36. Thereafter insert 50 is pushed further inwardly causing the rectilinear sides 54 of the restricted slot 55 of the opening 51 to enter groove 43 and removably straddle the reduced portion 44 of section 17 whereby the insert is removably interlocked with base section 17 and cooperates with the wall 14 to prevent longitudinal displacement of this base section, the closure or plug head 53' of the spring or insert 50 having shoulders 56 to limit the inward displacement of the insert while its arcuate wing portions 52 and the lower portion 54' resiliently or frictionally engage the walls of the bore of tube S. To remove the base section 17, head 53' is grasped and pulled outwardly, hence unlocking base section 17 by positioning opening 53 about the body of section 17 and the latter may be linearly removed from the tube S. In other aspects, the form according to Figs. 14-16 is along the lines of the embodiment illustrated in Fig. 11.

According to the form illustrated in Fig. 17, base section 17 is first positioned in the aligned openings 15 and 36. Thereafter split spring body 60 of the locking closure plug or insert generally denoted 61 may be inserted into the bore of tube S whereby the spaced prongs 62

are received in the groove 43 and straddle the reduced portion 44 of base section 17 after which the sides of the elongated opening 63 enter groove 43 and interlock with the sides of the reduced portion or neck 44. The tail portion 64 embodying the prongs 62 is a hollow member having its top wall 65 and its depending arcuate wings as 66 frictionally and removably cooperating with the walls of the tube S and although its upper wall 65 bears against the upper wall 14 to prevent longitudinal displacement of the base section 17, the head 67 is hollow and of the type illustrated in Fig. 16 and includes stop shoulder 68 to limit the insertion of the plug into the bore of tube S. To remove the base section 17, head 67 is grasped and shifted outwardly, thus freeing or unlocking section 17 and the latter may be slidably withdrawn from the tube. Otherwise the form illustrated in Fig. 17 is along the lines shown in Fig. 16.

By the several arrangements disclosed the base sections are not only removably interlocked against rotation but are further removably held against accidental longitudinal displacement and against withdrawal from the supporting tube S although sustained against tilting by the closely confining wall of the bore or opening 15.

Various changes may be made in the details of construction and arrangement of parts without departing from the spirit of the invention or sacrificing any of the advantages thereof inherent therein.

I claim:

1. In a loose leaf binder, a post, a tubular member having a lower flattened wall including key receiving means and having an upper flattened wall including an opening registering with said key receiving means, said post adapted to be received into said tubular member through said opening and having terminal key means removably and non-rotatably interlocked with said key receiving means, and locking means movably carried by said post and cooperating with said upper wall to preclude withdrawal of said post from said tubular member.
2. In a loose leaf binder, a cylindrical post characterizing a base section, a tubular member having a lower flattened wall including non-circular key receiving means and having an upper flattened wall including a circular opening registering with said key receiving means, said post adapted to be removably received into said tubular member through said opening and having non-circular key terminal means removably and non-rotatably interlocked with said key receiving means, and locking means movably carried by said base section and cooperating with said upper wall to preclude withdrawal of said post from said tubular member.
3. In a loose leaf binder, a post, a tubular member having a lower flattened wall including key receiving means and having an upper flattened wall including an opening registering with said key receiving means, said post adapted to be received into said tubular member through said opening and having terminal key means removably and non-rotatably interlocked with said key receiving means, and locking means rotatably carried by said post and having wing means removably interposed between said upper and lower walls to preclude withdrawal of said post from said tubular member.
4. In a loose leaf binder, a cylindrical post, a tubular member having a lower flattened wall including at least in part non-circular key re-

ceiving means and having an upper flattened wall including a circular opening registering with said key receiving means, said post adapted in part to be received into said tubular member through said opening and having depending and at least in part non-circular key means removably and non-rotatably interlocked with said key receiving means, and a sleeve closely and rotatably surrounding said post and having a wing interposed between said upper and lower walls and frictionally cooperating with said upper wall to preclude withdrawal of said post from said tubular member.

5. In a loose leaf binder, a post, a tubular member having a lower flattened wall including key receiving means and having an upper flattened wall including an opening registering with said key receiving means and including a notch merging with said opening, said post adapted to be received into said tubular member through said opening and having depending key means removably and non-rotatably interlocked with said key receiving means, and a sleeve closely and rotatably surrounding said post and closely and removably receivable in said opening and having a wing portion removably receivable in said notch and removably receivable between said lower and upper walls and cooperating with said upper wall to preclude withdrawal of said post from said tubular member.

6. In a loose leaf binder, a threaded post, a tubular member having a lower flattened wall including key receiving means and having an upper flattened wall including an opening registering with said key receiving means and including a notch merging with said opening, said post adapted to be removably received into said tubular member through said opening and having depending key means removably and non-rotatably interlocked with said key receiving means, a sleeve longer than the height of said member and closely and rotatably surrounding said post and in part closely and removably receivable in said opening and having a wing portion removably receivable in said notch and removably receivable between said lower and upper walls and cooperating with said upper wall to preclude withdrawal of said post from said tubular member, and said sleeve having an accessible slot.

7. In combination, a tubular member having a lower flattened wall including in part non-circular key receiving means and having an upper flattened wall including a circular opening registering with said key receiving means and including a notch merging with said opening, a circular threaded post adapted to be removably received into said tubular member through said opening and having depending key means removably and non-rotatably interlocked with said key receiving means, and a longitudinally split annular sleeve longer than the height of said member and closely and rotatably surrounding said post and closely and removably receivable in said opening and having a laterally extending wing portion removably receivable in said notch and removably receivable between said lower and upper walls and having means cooperating with said upper wall to preclude withdrawal of said post from said tubular member.

8. In combination, a tubular member having a lower flattened wall including key receiving means and having an upper flattened wall including an opening registering with said key receiving means, a threaded post longer than the height of

said member and adapted to be closely and removably received into said tubular member through said opening and having terminal key means removably and non-rotatably interlocked with said key receiving means and having an intermediately arranged reduced portion, and locking means closely and removably straddling said reduced portion and cooperating with said upper wall to preclude withdrawal of said post from said tubular member.

9. In combination, a tubular member having a lower flattened wall including key receiving means and having an upper flattened wall including an opening registering with said key receiving means, a threaded post longer than the height of said member and adapted to be closely and removably received into said tubular member through said opening and having terminal key means removably and non-rotatably interlocked with said key receiving means and having a reduced part defining a groove with the body of said post, and spring locking means receivable in said groove and removably straddling said reduced part and cooperating with said upper wall to preclude withdrawal of said post from said tubular member.

10. In combination, a tubular member having a lower flattened wall including key receiving means and having an upper flattened wall including an opening registering with said key receiving means, a threaded post longer than the height of said member and adapted to be closely and removably received into said tubular member through said opening and having terminal key means removably and non-rotatably interlocked with said key receiving means and having a reduced part defining a groove with the body of said post, and a looped spring removably receivable in said groove and resiliently straddling said reduced part and cooperating with said upper wall to preclude withdrawal of said post from said tubular member.

11. In combination, a tubular member having a lower flattened wall including key receiving means and having an upper flattened wall including an opening registering with said key receiving means, a threaded post longer than the height of said member and adapted to be closely and removably received into said tubular member through said opening and having terminal key means removably and non-rotatably interlocked with said key receiving means and having a reduced part defining a groove with the body of said post, and a slidably guided spring removably receivable in the bore of said tubular member and having an opening for receiving said post and having a slotted portion removably receivable in said groove to straddle said reduced part and cooperating with said upper wall to preclude the withdrawal of said post from said tubular member.

12. In combination, a tubular member having a lower flattened wall including key receiving means and having an upper flattened wall including an opening registering with said key receiving means, a threaded post longer than the height of said member and adapted to be closely and removably received into said tubular member through said opening and having terminal key means removably and non-rotatably interlocked with said key receiving means and having a reduced part defining a groove with the body of said post, and a slidably guided spring removably receivable in the bore of said tubular member and having an opening for removably receiv-

ing said post and having a slotted portion removably receivable in said groove to straddle said reduced part and cooperating with said upper wall to preclude the withdrawal of said post from said tubular member, said spring having a head characterizing closure means for one end of said bore.

13. In combination, a tubular member having a lower flattened wall including key receiving means and having an upper flattened wall including an opening registering with said key receiving means, a threaded post longer than the height of said member and adapted to be closely and removably received into said tubular member through said opening and having terminal key means removably and non-rotatably interlocked with said key receiving means and having a reduced part defining a groove with the body of post, and a slidably guided spring removably receivable in the bore of said tubular member and having an opening for removably receiving said post and having a slotted portion removably receivable in said groove to removably straddle said reduced part and cooperating with said upper wall to preclude the withdrawal of said post from said tubular member, said spring having a head characterizing closure means for one end of said bore and having depending wings slidably and frictionally engaging the wall of said bore.

14. In combination, a tubular member having a lower flattened wall including key receiving means and having an upper flattened wall including an opening registering with said key receiving means, a threaded post longer than the height of said member and adapted to be closely and removably received into said tubular member through said opening and having terminal key means removably and non-rotatably interlocked with said key receiving means and having a reduced part defining a groove with the body of said post, and a slidably guided spring removably receivable in the bore of said tubular member and having spaced resilient prongs for removably receiving said post and having a slotted portion removably receivable in said groove to removably and yieldingly straddle said reduced part and cooperating with said upper wall to preclude the withdrawal of said post from said tubular member.

15. In combination, a tubular member having a lower flattened wall including key receiving means and having an upper flattened wall including an opening registering with said key receiving means, a threaded post longer than the height of said member and adapted to be closely and removably received into said tubular member through said opening and having terminal key means removably and non-rotatably interlocked with said key receiving means and having a reduced part defining a groove with the body of said post, and a slidably guided spring removably receivable in the bore of said tubular member and having spaced prongs for removably receiving said post and having a slotted portion removably receivable in said groove to straddle and removably interlock with said reduced part and cooperating with said upper wall to preclude the withdrawal of said post from said tubular member, said spring having a head serving as closure means for one end of said bore.

16. In combination, a tubular member having a lower flattened wall including at least in part non-circular terminal receiving means and having an upper flattened wall including a cylindrical opening in vertical alinement with said key re-

ceiving means and including a notch in communication with said opening, a threaded and cylindrical post adapted to be removably received in said tubular member through said opening and having at least in part non-circular terminal means removably interlocking with said terminal receiving means, and a sleeve longer than the height of said member and closely and rotatably surrounding said post and in part closely and removably receivable in said opening and extending above said upper flattened wall and having a wing portion removably receivable in said notch and removably receivable between said upper and lower walls and having means cooperating with said upper wall to preclude withdrawal of said post from said tubular member.

17. In combination, a tubular member having a lower flattened wall including at least in part non-circular terminal receiving means and having an upper flattened wall including a cylindrical opening in vertical alinement with said key receiving means and including a notch in communication with said opening, a threaded and cylindrical post adapted to be removably received in said tubular member through said opening and having at least in part non-circular terminal means removably interlocking with said terminal receiving means, and a longitudinally split annular sleeve longer than the height of said member and closely and rotatably surrounding said post and in part closely and removably receivable in said opening and extending above said upper flattened wall and having a wing portion removably receivable in said notch and removably receivable between said upper and lower walls and having means frictionally cooperating with said upper wall to preclude withdrawal of said post from said tubular member.

18. In combination, a tubular member having a lower flattened wall including at least in part non-circular key receiving means and having an upper flattened wall including a cylindrical opening in vertical alinement with said key receiving means and including a notch in communication with said opening, a threaded and cylindrical post adapted to be removably received in said tubular member through said opening and having at least in part non-circular terminal key means removably interlocking with said key receiving means, and a longitudinally split annular sleeve longer than the height of said member and closely and rotatably surrounding said post and in part closely and removably receivable in said opening and extending above said upper flattened wall and having a wing portion removably receivable in said notch and removably receivable between said upper and lower walls and having means cooperating with said upper wall to preclude withdrawal of said post from said tubular member.

19. In combination, a tubular member having a lower flattened wall including at least in part non-circular key receiving means and having an upper flattened wall including a cylindrical opening in vertical alinement with said key receiving means and including a notch in communication with said opening, a threaded and cylindrical post adapted to be removably received in said tubular member through said opening having an annular flange and having at least in part non-circular terminal key means removably interlocked with said key receiving means, and a longitudinally split annular sleeve seated on said flange and longer than the height of said member and closely and rotatably surrounding said post and in part

closely and removably receivable in said opening and extending above said upper flattened wall and having a wing portion removably receivable in said notch and removably receivable between said upper and lower walls and having means cooperating with said upper wall to preclude withdrawal of said post from said tubular member.

20. In combination, a tubular member having a lower flattened wall including at least in part non-circular and spaced key receiving means and having an upper flattened wall including a cylindrical opening in vertical alinement with said key receiving means and including a notch in communication with said opening, a threaded and cylindrical post adapted to be removably received in said tubular member through said opening and having spaced keys removably interlocked with said spaced key receiving means, and a longitudinally split annular sleeve longer than the height of said member and closely and rotatably surrounding said post and in part closely and removably receivable in said opening and extending above said upper flattened wall and having a wing portion removably receivable in said notch and removably receivable between said upper and lower walls and having means cooperating with said upper wall to preclude withdrawal of said post from said tubular member.

21. In combination, a tubular member having a lower flattened wall including key receiving means and having an upper flattened wall including an opening in alinement with said key receiving means, a threaded post longer than the height of said member and adapted to be closely and removably received into said tubular member through said opening and having terminal key means removably and non-rotatably interlocked with said key receiving means and having a reduced part defining a groove with the body of said post, and a hair pin spring having spaced arms in part removably receivable in said groove and having outwardly convex and inwardly concaved portions resiliently straddling said reduced part and cooperating with said upper wall to preclude withdrawal of said post from said tubular member.

22. In combination, a tubular member having a lower flattened wall including key receiving means and having an upper flattened wall including an opening registering with said key receiving means, a threaded post longer than the height of said member and adapted to be closely and removably received into said tubular member through said opening and having terminal key means removably and non-rotatably interlocked with said key receiving means and having a reduced part defining a groove with the body of said post, and a spring removably re-

ceivable in said tubular member and having spaced means fitting into said groove to closely and removably straddle said reduced portion and cooperating with said upper wall to preclude removal of said post from said tubular member.

23. In combination, a tubular member having a lower flattened wall including key receiving means and having an upper flattened wall including an opening registering with said key receiving means, a threaded post longer than the height of said member and adapted to be closely and removably received into said tubular member through said opening and having terminal key means removably and non-rotatably interlocked with said key receiving means and having a reduced part defining a groove with the body of said post, and a slidably guided spring removably receivable in said tubular member and having spaced prongs defining a slot and including free tapered terminals adapted to be led into said groove prior to reception by the latter of the spaced sides of said slot and having an intermediate portion including an opening communicating with said slot and embodying spaced sides closely and removably straddling said reduced part, and said intermediate portion constituting means cooperating with said upper wall to preclude withdrawal of said post from said tubular member.
